US00D915484S

(12) **United States Design Patent** (10) **Patent No.:** **US D915,484 S**
(45) **Date of Patent:** **** Apr. 6, 2021**

(54) **INTERSTAGE SCREEN BASKET**

(71) Applicant: **DERRICK CORPORATION**, Buffalo, NY (US)

(72) Inventors: **James R. Colgrove**, East Aurora, NY (US); **Clifford C. Smith**, North Collins, NY (US)

(73) Assignee: **DERRICK CORPORATION**, Buffalo, NY (US)

(**) Term: **15 Years**

(21) Appl. No.: **29/671,960**

(22) Filed: **Nov. 30, 2018**

Related U.S. Application Data

(63) Continuation of application No. 16/151,909, filed on Oct. 4, 2018, which is a continuation-in-part of application No. 16/001,755, filed on Jun. 6, 2018, and a continuation of application No. 16/001,755, filed on Jun. 6, 2018.

(57) **CLAIM**

The ornamental design for an interstage screen basket, as shown and described.

DESCRIPTION

FIG. 1 is a top perspective view of a first embodiment of an interstage screen basket;

FIG. 2 is a right side view thereof;

FIG. 3 is a left view thereof;

FIG. 4 is a front view thereof;

FIG. 5 is a back view thereof;

FIG. 6 is a top view thereof; and

FIG. 7 is a bottom view thereof.

FIG. 8 is a top perspective view of a second embodiment of an interstage screen basket;

FIG. 9 is a right side view thereof;

FIG. 10 is a left view thereof;

FIG. 11 is a front view thereof;

FIG. 12 is a back view thereof;

FIG. 13 is a top view thereof; and

FIG. 14 is a bottom view thereof.

FIG. 15 is an enlarged partial view of the Section 15 depicted in back view FIG. 5; and,

FIG. 16 is an enlarged partial view of the Section 16 depicted in back view FIG. 12.
